FIG. 1

FIG. 2

FIGURE 1 is a perspective view of a packaging tray, showing my new design; and

FIGURE 2 is a vertical sectional view taken substantially on the plane of line 2—2 of FIGURE 1.

The tray is formed of substantially paper-thin molded plastic in which the undersurface is a reverse image of that shown in FIGURE 1.

The characteristic features of my design reside in vertically corrugated double walls integral with a corrugated, raised bottom having corrugations continuing through vertical partitions having a shallow scalloped upper edge in combination with low profiled side walls which merge into raised end walls.

I claim:

The ornamental design for a packaging tray, as shown and described.
